DESIGN FOR A RING

Salomon dit Charles Arpels, Paris, France, assignor to Société Van Cleef & Arpels, Paris, France, a corporation of France

Application March 26, 1936, Serial No. 61,797

Term of patent 7 years

To all whom it may concern:

Be it known that I, Salomon dit Charles Arpels, a citizen of the Republic of France, residing at Paris, 22, Place Vendôme, in the said Republic, have invented a new, original, and ornamental Design for a Ring, of which the following is a specification, reference being had to the accompanying drawing, forming part thereof.

In the accompanying drawing:

Fig. 1 is a top plan view,
Fig. 2 is a side view, and
Fig. 3 is a perspective view of a ring showing my new design.

I claim:

The ornamental design for a ring, as shown.
In testimony whereof, I have affixed my signature.

SALOMON DIT CHARLES ARPELS.
